Inventor:

John Zebley, by
Emile Russell, his Atty.

UNITED STATES PATENT OFFICE.

JOHN ZEBLEY, OF PHILADELPHIA, PENNSYLVANIA.

DESIGN FOR FRINGE.

SPECIFICATION forming part of Design No. 15,483, dated October 21, 1884.

Application filed July 19, 1884. Term of patent 3½ years.

To all whom it may concern:

Be it known that I, JOHN ZEBLEY, of Philadelphia, in the county of Philadelphia, and in the State of Pennsylvania, have invented a certain new and useful Design for Fringe for Window-Shade Trimming; and I do hereby declare that the following is a full, clear, and exact description of the invention, reference being had to the accompanying drawing, in which is shown my new design for frill-fringe for window-shade trimming.

As shown in the drawing, my invention embraces a design for frill-fringe which shows a heading or roving, A, from which depend the broad strands B B, made up of several of the smaller strands *bb* taken together. The broad strands B B are shown as divided into pairs, in each of which the strands are shown as passing in opposite directions, one over the other. They then pass, respectively, under and over the strands from the adjacent pairs. The strands B B from opposite sides of alter-

nate pairs are shown as connected together, after passing over and under the intervening strands, by knots or tufts of loops C. The ends of the connected strands are shown hanging down below such knots or tufts.

Having thus described my invention, what I claim is—

The design for a fringe, showing the roving A, the strands B B depending therefrom as divided into pairs, the two strands of each pair as crossing each other in opposite directions, and the outer or opposite strands of alternate pairs as connected together by knots or tufts 35 of loops, and depending below such loops or tufts, as shown and described.

In testimony that I claim the foregoing I have hereunto set my hand this 28th day of June, A. D. 1884.

JOHN ZEBLEY.
